[57] **CLAIM**

The ornamental design for a housing for an electrical connector, as shown and described.

DESCRIPTION

FIG. 1 is a front perspective view of a housing for an electrical connector showing our new design;

FIG. 2 is rear perspective view thereof;

FIG. 3 is a front elevation view thereof;

FIG. 4 is a rear elevation view thereof;

FIG. 5 is left side elevation view thereof, it being understood that the right side is a mirror image of that shown;

FIG. 6 is a top plan view thereof; and

FIG. 7 is a bottom plan view thereof.
